M. F. KEVLIN

SLATTED CONVEYER OR APRON AND THE LIKE

Filed Dec. 4, 1923

Inventor:
Matthew F. Kevlin
by Chas. F. Randall
Attorney.

UNITED STATES PATENT OFFICE.

MATHEW F. KEVLIN, OF SPRINGFIELD, VERMONT, ASSIGNOR TO THE JAMES HUNTER MACHINE COMPANY, OF NORTH ADAMS, MASSACHUSETTS, A CORPORATION OF MASSACHUSETTS.

SLATTED CONVEYER OR APRON AND THE LIKE.

Application filed December 4, 1923. Serial No. 678,473.

To all whom it may concern.:

Be it known that I, MATHEW F. KEVLIN, a citizen of the United States, residing at Springfield, in the county of Windsor, State 5 of Vermont, have invented a certain new and useful Improvement in Slatted Conveyers or Aprons and the like, of which the following is a specification, reference being had therein to the accompanying drawings.

10 The invention has relation to the slatted conveyers or aprons which are used in wool scourers, mixing pickers, and various other machines, and in particular to the slats which are combined with flexible connecting 15 means, such as chains or belts, to form such conveyers or aprons.

In accordance with the invention the transversely extending slats of a conveyer or apron are respectively formed with a 20 longitudinal groove or depression between raised ribs, and the rivets or other fastening means which attach the slats to the connecting means are applied between the two raised ribs, with the ends of the rivets or 25 other fastening means contained within the longitudinal groove or depression.

An object of the invention is to provide a construction permitting a conveyer or apron to work in close contact with the surface of 30 a roll, for instance the bottom squeeze-roll of a wool scourer, without wear of the heads of the rivets or other fastening means which combine the slats with the flexible connecting means. It is customary to set a conveyer or apron to cause the slats to make the 35 close contact just mentioned with the surface of the adjacent roll, but in cases in which the heads of the rivets are exposed at the surfaces of the slats to contact with the 40 said roll this contact results in the wearing away of the heads or ends of the rivets so that they cease to hold the slats to the chains or belt. In some cases in practice slats have been countersunk around the rivet heads or 45 ends to enable the said heads or ends to be depressed below the slat-surface which contacts with the roll, but this entails expense in making a conveyer or apron, and also renders inconvenient the removal of a slat, 50 which sometimes is necessary. When such countersinking around the rivet heads or ends has been resorted to in constructing the apron it becomes necessary, in effecting such removal, to dig away the wood to afford

access to the depressed heads or ends for the purpose of disconnecting the slat from the connecting means; which results in injury to the slat and more or less incapacitates it for further use, as for instance for the purpose of making repairs.

Another object of the invention is to provide for securing two wiping operations by each slat, thereby keeping the roll cleaner than in the case of the single wiping operation that is accomplished by the ordinary 65 slat in use heretofore. In ordinary practice, the employment of narrow slats, close together and proportionately increased in number, in the undertaking to improve the wiping action, has involved the following 70 drawbacks: It necessitates the use of a light slat which is subject to warping and to breakage, and it involves also the use of a lighter chain in the case of a conveyer or 75 apron comprising flexible chains. In the case of a conveyer comprising slats attached to a belt the belt would not have to be any lighter, but the drawback with respect to warping and tendency to breakage would 80 exist. When a slat warps so as to bulge out toward the roll, the conveyer or apron has to be spaced farther away from the surface of the roll, with the result that the slats which remain straight are separated too far 85 from the surface of the roll. If a slat warps the other way, it leaves an opening or hole between such slat and the surface of the roll.

An illustrative embodiment of the invention is shown in the accompanying drawings, 90 in which,

Fig. 1 is a diagrammatic view of the top and bottom squeeze-rolls of a wool scourer or the like machine, and a portion of a conveyer or apron cooperating therewith, illustrating the connection in which the present invention is applied.

Fig. 2 is a sectional view of a slat formed according to the invention, showing an attached link of the flexible connecting chain, 100 the section being on line 2—2 of Fig. 4.

Fig. 3 is a view similar to Fig. 2, the section being made on line 3—3 of Fig. 4.

Fig. 4 is a bottom view of a portion of a slat and a chain link combined therewith.

Having reference to the drawings,—

Fig. 1 thereof is intended to illustrate the relations between a conveyer or apron 23,

in passing around a guide-roll 24, and the lower roll, 22, of the pair of squeeze-rolls 21, 22, of a wool scourer or the like machine. The remaining views show the special features of construction which are more particularly involved in the invention.

The slat 1 is formed with a deeply-sunk longitudinal groove 11 on its acting surface, between two raised ribs 2, 2, preferably 10 rounded as shown.

The connecting means indicated in the present instance is the familiar detachable-link chain, commonly termed a link-belt. The fastening means by which the chain-link 3 that is shown in the drawings is illustrated as attached to the slat 1 comprises rivets 6, 6, which pass through holes 4, 4, in the lugs 5, 5, at opposite ends of the link 3, up through the material of the slat, and 20 out into the longitudinal groove 11 of such slat. Within such groove, a washer 7 is applied to the end of each rivet, and such end is burred or headed over in the usual manner, as at 8. The location of the rivet-heads and washers in the longitudinal depression of the improved slat, places them where they are protected against wear through contact with a roll. It allows the burred or headed-over ends 8, 8, of the 30 rivets 6, 6, to stand up slightly above the surface of the adjoining portion of the slat,

so that when it is necessary to cut the rivets so as to detach the slat, this may be done easily by means of a chisel without any injury to the material of the slat.

35

The ribs at opposite sides of the depression effect the two contacting or wiping operations to which reference has been made, as they pass the roll aforesaid, instead of the single contact in the case of the ordinary slat, thus doubling the efficiency of the conveyer or apron in this respect over that of prior constructions.

40

What I claim as my invention is,—

1. The combination with a roll, of a flexible conveyer or apron cooperating therewith and comprising transversely extending slats each having a plurality of raised wiping ribs adapted to wipe adherent matter from the periphery of the roll.

45

2. The combination with a roll, of a flexible conveyer or apron cooperating therewith and comprising transversely extending slats each having a plurality of raised wiping ribs adapted to wipe adherent matter from the periphery of the roll, means for combining such slats in series, and rivets securing each slat to the combining means, said rivets headed down within a longitudinal groove between said ribs and thereby 50 protected against contact with the roll.

55

MATHEW F. KEVLIN.
